UNITED STATES PATENT OFFICE.

LEONARD S. BALUTA AND OSCAR W. ALTHOFF, OF BERWICK, PENNSYLVANIA.

CIRCUIT MAKER AND BREAKER.

Application filed December 1, 1921. Serial No. 519,199.

To all whom it may concern:

Be it known that we, LEONARD S. BALUTA and OSCAR W. ALTHOFF, citizens of the United States, residing at Berwick, in the county of Columbia and State of Pennsylvania, have invented certain new and useful Improvements in Circuit Makers and Breakers, of which the following is a specification.

This invention relates to circuit closers and the primary object of the present invention is to provide a novel circuit closer which is particularly adapted for use in connection with auxiliary lighting systems for theaters and the like, such as disclosed in our pending application filed June 28, 1921, Serial Number 481,080, but which is susceptible of other uses and which includes a novelly arranged solenoid and armature for insuring an even pull on the armature, when the solenoid is energized and a novel means for adjustably supporting the armature operated contact making lever, so that the same can be set at different points for changing the relative position of the armature in relation to the solenoid and the contact points in relation to each other, whereby the circuit closer is given great flexibility over wide ranges of electric voltage.

Other objects of the invention are first to provide a novel guide for the lever operating armature, so that the same will be held centered at all times for free movement and second novel means for supporting the contact points, where the same can be adjusted independently of each other and in relation to each other.

A still further object of the invention is to provide a novel circuit making and breaking device of the above character, which is of simple and durable construction and which can be placed upon the market at a minimum cost.

With these and other objects in view, the invention consists in the novel construction, arrangement and formation of parts, as will be hereinafter more specifically described, claimed and illustrated in the accompanying drawings, forming a part of this specification, in which drawings:

Figure 1 is a front elevation of the improved circuit making and breaking device.

Fig. 2 is a longitudinal central section through the same.

Fig. 3 is a vertical transverse section through the circuit maker and breaker taken on the line 3—3 of Figure 1.

Fig. 4 is a fragmentary transverse vertical section taken on the line 4—4 of Figure 1.

Fig. 5 is a fragmentary enlarged longitudinal section through a portion of the circuit maker and breaker illustrating the means for adjustably supporting the contact points, and

Fig. 6 is a detail perspective view of the novel guide for the contact making lever, which is operated by the solenoid.

Referring to the drawings in detail, wherein similar reference characters designate corresponding parts throughout the several views the letter A generally indicates the improved circuit making device, which may be mounted on a face plate 10.

The face plate 10 is preferably formed of non-electric conducting material and is of a substantially rectangular configuration of the desired size and can be readily attached to any suitable support if desirable. The face plate 10 adjacent to one transverse edge thereof has secured thereto by suitable fastening elements 11 the operating solenoid 12 which can be of the usual or of a special construction.

The coil or solenoid 12 may be wound to any capacity and resistance to suit conditions for which it is intended and receives in the bore of the spool 12' thereof the armature 13. This core or armature 13 is formed of a relatively smaller diameter than the bore of the spool 12' so as to eliminate friction in the spool and thereby allow for an even pull on the armature. This armature 13 is held centered in the solenoid by means of a weight 14 which is threaded or otherwise secured to the lower end thereof. This weight 14 also tends to hold and to move the armature to the lower end of the solenoid when the solenoid is not energized. The armature 13 adjacent to the lower end thereof is flattened and fitted in the bifurcated end of a bell crank lever 15. A pivot pin 16 serves as means for connecting the armature 13 with the bell crank 15 and as stated the weight 14 holds the armature in a vertical position at all times on said pivot pin.

The bell crank lever 15 is disposed mainly in the space 17 of a U-shaped frame 18, which is also preferably made of non-electric conducting material. This frame has one end non-electrically connected with the solenoid 12 by means of suitable fastening elements or the like 19. It thus can be seen

that the circuit closer in itself is a complete unit and that the unit may be held in position on the face plate 10 by means of the fastening elements 11. The frame 18 includes parallel spaced arms 20 and 21 which have formed therein adjacent to the connecting portion 18' thereof a plurality of aligned opening 22 any one of which is adapted to align with any one of the openings 23 formed in the bell crank 15. The openings 22 and 23 are positioned different distances apart and are adapted to receive the removable pivot pin 24. By changing the position of the pivot pin 24 in the various openings 15 22 and 23 the core or armature 13 is disposed at varying distances within the solenoid 12, so that the contact point 25 carried by depending short arm 26 of the bell crank 15 can be adjusted in relation to the contact point 27 carried by the supporting bar 28 which is held in position by contact bolt 29. One end of the contact bolt 29 is extended beyond the supporting frame to form a binding terminal. These contact points 25 and 27 are held in place by suitable nuts 29' which are threaded on the stems of the contact points. The active faces of the contact points 27 and 25 may be formed of some metal, which is particularly well adaptable 30 for forming an electric contact.

The solenoid 12 has connected to the terminals 31 thereof the lead wires 32 and 33 which may lead from a main circuit. The conducting bolt 29 has connected thereto a wire 34 and the pivot bolt 24 has connected thereto a wire 35 and these wires 34 and 35 may form the lead wires of an auxiliary circuit.

In order to establish a good contact between the pivot pin 24 and the bell crank 15 and in order to hold the bell crank 15 in spaced relation to the arms 20 and 21 of the frame 18, a resilient clip 36 is provided. This resilient clip is of a substantially U-form and includes inwardly bowed arms 37 which are slotted intermediate their ends as at 38 for receiving and engaging the pivot bolt 24. It can be seen that the arms 37 snugly engage the inner faces of the arms 20 and 21 of the frame 18 and the opposite faces of the lever 15.

In operation of the improved circuit closer when the circuit of the solenoid is broken the weight 14 will pull the armature downward within the solenoid and rock the lever 15 upon its pivot 24. This will bring the contact points 25 and 27 into firm contact thus establishing an electrical communication between the wires 34 and 35.

As soon as the main circuit is closed the solenoid will become again energized and thus attract the armature 13 and move the

contact point 25 out of engagement with the contact point 27, thus again breaking the circuit between the wires 34 and 35.

From the foregoing description it can be seen that a novel circuit maker and breaker has been provided of exceptionally simple and durable construction and in which the contact making and breaking lever may be 70 adjusted so as to suit varying conditions.

Changes in details may be made without departing from the spirit or scope of this invention; but,

We claim:

1. A circuit maker and breaker comprising a solenoid, a frame, including a pair of spaced arms disposed at each side of the axis of said solenoid, a bell crank lever disposed between said arms, the arms and the bell 80 crank lever having a plurality of spaced openings formed therein, a pivot bolt for positioning in any one of said registering openings, the pivot bolt forming a binding post, a removable spring clip arranged to 85 engage the pivot bolt, the lever and the arms, a second binding post, a stationary contact point electrically connected with the second binding post, a movable contact carried by the lever electrically connected with the first 90 binding post through said pivot bolt, spring and lever, and an armature carried by said lever and extending into said solenoid.

2. A circuit maker and breaker comprising a solenoid, a frame, including a pair of 95 spaced arms disposed at each side of the axis of said solenoid, a bell crank lever disposed between said arms, the arms and the bell crank lever having a plurality of spaced openings formed therein, a pivot bolt for 100 positioning in any one of said registering openings, the pivot bolt forming a binding post, a second binding post, a stationary contact point electrically connected with the second binding post, a movable contact carried by the lever electrically connected with the first 105 binding post through said pivot bolt and lever, and an armature carried by said lever and extending into said solenoid.

3. A circuit maker and breaker comprising in combination, a lever having a horizontal axis of oscillation, a vertically disposed solenoid, an armature extending upwardly into said solenoid and pivotally carried by the free end portion of said lever, a 115 stationary contact, a movable contact for cooperation therewith, carried by said lever, and a weight carried by said armature having the dual function of centering said armature in said solenoid and holding said contacts in engagement due to the force of 120 gravity, when said solenoid is not energized.

LEONARD S. BALUTA.
